UNITED STATES PATENT OFFICE.

HARTSELL H. CROSS AND SAMUEL McDANIELS, OF HENDRICKS, WEST VIRGINIA.

GLOVE.

1,192,042.

Specification of Letters Patent. Patented July 25, 1916.

Application filed April 10, 1914. Serial No. 830,990.

To all whom it may concern:

Be it known that we, HARTSELL H. CROSS and SAMUEL McDANIELS, citizens of the United States, residing at Hendricks, in the 5 county of Tucker, and State of West Virginia, have invented new and useful Improvements in Gloves, of which the following is a specification.

This invention relates to gloves and more 10 particularly to gauntlet gloves.

The principal object of this invention is to provide a shield or reinforcement which protects and prevents wear upon the wrist of the glove or at that point where the 15 gauntlet is connected to the glove proper.

It is a well known fact that brakemen wear their gloves at the wrist more than at any other one point and it is the object of this invention to obviate this difficulty and 20 at the same time to provide means for protecting the connection of the gauntlet with the glove.

Another object of the invention is the provision of a glove having a removable 25 gauntlet.

Further objects of the invention will appear as the following description is read in connection with the accompanying drawing, which forms a part of this application, and 30 in which:—

Figure 1 is a perspective view looking at the inside of the glove. Fig. 2 is a plan view of the glove looking at the back thereof and with the gauntlet partially attached. 35 Fig. 3 is a longitudinal sectional view taken on the irregular line 3—3 of Fig. 2.

Referring more particularly to the drawing, 1 represents the glove which is here shown to be a finger glove although it will 40 be well understood that the invention may be applied to mitts if desired. The upper portion of the glove has stitched thereto a wrist band 2 which reinforces the upper edge and secured to this wrist band are a plurality of 45 headed studs 3 which coact with the socket members 4 on the gauntlet 5. This gauntlet comprises an arcuate segment having parallel side edges and diverging end edges, as shown in Fig. 2, the lower side edge being provided with the socket members 4 which coact with the studs on the wrist band 50

to fasten the lower edge of the gauntlet around the wrist band, as will be well understood.

The end edges of the gauntlet are provided with coacting head and socket fasteners 6 and 7 which serve to join the edges of the segment together in gauntlet form. Thus it will be understood that the gauntlet may be attached to or removed from the 55 glove when desired and as one set of gauntlets will outwear three or four pairs of gloves it can be readily seen that considerable advantage is afforded the consumer.

Stitched to the wrist band upon the inner side of the glove is a flap 8 preferably constructed of heavier material than the glove so as to withstand considerable wear and yet being flexible enough to permit free movement. The free edge of the flap 8 is 60 provided with socket members 9 to coact with the stud or head members 10 secured to the gauntlet above the socket members 4 and upon the outside thereof. When this flap is in operative position it overlies the 65 head and socket fasteners on the inner side of the wrist band and connects to the gauntlet, as shown in Fig. 3, whereby the connection between the gauntlet and the glove is not fully protected but the flap also serves 70 to hold the fasteners which join the gauntlet with the glove against accidental displacement.

It will be understood that a glove of this character may be worn with or without the 85 gauntlet, the flap 8 serving in the latter instance as a protector to the wrist, but the primary object is to use the flap in connection with removable or fixed gauntlets so as to protect the connection between the glove 90 and the gauntlet and to take up the wear at this point.

What is claimed is:—

In combination a glove, a wrist band reinforcing the upper portion thereof, a gauntlet, a plurality of stud members secured upon the outside of said gauntlet at one side thereof, a flap secured upon said wrist band, socket members carried by said flap, said flap adapted to extend around the inner 95 edge of said gauntlet whereby to cause said socket members to engage said stud mem- 100

bers, a plurality of socket members secured upon the lower edge of said gauntlet, a plurality of stud members secured upon said wrist band engageable by said last-named 5 socket members whereby to allow said gauntlet to be held folded around said wrist band to further reinforce said glove with its secured sides disposed at one side of said flap.

In testimony whereof we affix our signatures in presence of two witnesses.

HARTSELL H. CROSS.
SAM. McDANIELS.
